WALL MOUNTED LIGHTING FIXTURE

Van N. Marker, Chicago, Ill.

Application April 11, 1949, Serial No. 1,909

Term of patent 3½ years

(Cl. D48—4)

To all whom it may concern:

Be it known that I, Van N. Marker, a citizen of the United States of America, residing at Chicago, in the county of Cook and the State of Illinois, have invented a new, original, and ornamental Design for a Wall Mounted Lighting Fixture, of which the following is a specification, reference being had to the accompanying drawing, forming part thereof.

Figure 1 is a perspective view of a wall mounted lighting fixture, showing my new design.

Figure 2 is a front elevation thereof; and

Figure 3 is a cross section on the line 3—3 of Figure 2.

I claim:

The ornamental design for a wall mounted lighting fixture, as shown.

VAN N. MARKER.
